CIRCUIT INTERRUPTER

Benjamin P. Baker, Turtle Creek, Pa., assignor to
Westinghouse Electric Corporation, East Pitts-
burgh, Pa., a corporation of Pennsylvania

Application June 9, 1950, Serial No. 167,214

7 Claims. (Cl. 200—145)

1

This invention relates to circuit interrupters in general, and more particularly to arc-extinguishing structures therefor.

The general object of my invention is to provide an improved high-speed type of liquid-break oil circuit interrupter in which improved and more effective operation is obtained over the entire current range.

Another object is to provide an improved circuit interrupter of repeatable unit construction in which any number of units may be employed, being disposed in superimposed relation corresponding to the voltage requirements.

Another object is to provide an improved high-speed type of interrupter in which the overall length of the interrupter is reduced to a minimum by the employment of very effective arc-extinguishing units of the multi-orifice type.

A further object is to provide an improved circuit interrupter of the type specified in the immediately preceding paragraph in which improved liquid oil pumping means are employed to facilitate the interruption of low currents, such as charging currents, and to provide a flushing flow of oil through the units during high-current interruption.

Further objects and advantages will readily become apparent upon reading the following specification, taken in conjunction with the drawings, in which:

Figure 1 is a side elevational view of a circuit interrupter embodying my invention, partially in vertical section, the contact structure being shown in the closed circuit position;

Fig. 2 is an enlarged fragmentary vertical sectional view through the lower portion of one of the arc-extinguishing assemblies of Fig. 1, the view being taken along the line II—II of Fig. 4 looking in the direction of the arrows, and the contact structure being shown at an intermediate point in the opening operation;

Fig. 3 is a view similar to that of Fig. 2 but taken along the line III—III of Fig. 4 looking in the direction of the arrows, the contact structure being shown at an intermediate point in the opening operation;

Fig. 4 is a sectional view taken along the line IV—IV of Fig. 2;

Fig. 5 is a sectional view taken along the line V—V of Fig. 2; and

Fig. 6 is a fragmentary broken vertical sectional view of a modified type of arc-extinguishing unit taken along the line VI—VI of Fig. 4, the contact structure being shown in the fully open circuit position.

2

Referring to the drawings, and more particularly to Figure 1 thereof, the reference numeral 1 designates a tank filled to the level 2 with a suitable arc-extinguishing liquid 3, in this instance circuit-breaker oil. Depending from the cover 4 of the tank 1 are a pair of terminal bushings 5, 6 to the lower ends of which are secured identical arc-extinguishing assemblies, generally designated by the reference numeral 7.

Electrically interconnecting the two arc-extinguishing assemblies 7 is a conducting cross-bar 8 reciprocally actuated in a vertical direction by an insulating lift-rod 9.

Referring more particularly to Figs. 2—5, which more clearly disclose the internal construction of each arc-extinguishing assembly 7, it will be noted, with particular attention being directed to Fig. 2, that each arc-extinguishing assembly 7 comprises a pair of arc-extinguishing units 10 disposed in superimposed relation and serially connected into the circuit. Each arc-extinguishing unit 10 includes suitable contact structure comprising a relatively stationary pressure-generating contact 11, an intermediate contact 12 and a lower movable interrupting contact 13. The interrupting contacts 13 for each arc-extinguishing assembly 7 are threadedly secured, as at 14, to metallic plates 15, 15a. The plates 15, 15a are rigidly secured to a pair of longitudinally extending insulating operating rods 16. The lowermost plate 15a has a relatively stationary disconnect contact 17 associated therewith, which makes abutting engagement, during the closing operation and also during the initial portion of the opening operation, with a movable rod-shaped disconnect contact 18, the latter being disposed at each extremity of the cross-bar 8. Thus upward closing motion of the lift-rod 9 and cross-bar 8 causes the movable disconnect contact 18 to strike the relatively stationary disconnect contact 17 to pick up the plates 15, 15a the latter being interconnected by the movable operating rods 16, and move the contacts 11, 12 and 13 to their closed circuit position, as shown more clearly in Fig. 1.

Associated with the intermediate plate 15 (Fig. 2) are a pair of movable cup-shaped insulating pistons 20 having upper flange portions 21. The pistons 20 slide through apertures 22 provided in the intermediate plate 15 and are biased downwardly in a pumping direction by a pair of compression springs 23. The lower ends of the compression springs 23 seat at the lower ends 24 of the pistons 20, and the upper ends of the compression springs 23 seat against the lower

metallic plate 25 of the upper unit 10 of the assemblage 7.

Disposed adjacent the lower ends 24 of the pumping pistons 20 are valves 26 biased closed by springs 27, and only opened during upward closing charging movement of the pistons 20.

A pair of resilient split contact tubes 28 (Fig. 5) are threadedly secured, as at 29, to the top metallic plate 30 of the lower arc-extinguishing unit 10. These tubes 28 pass through apertures 31 provided in the conducting intermediate plate 15 of the assemblage 7, and serve to provide an electrical connection between the intermediate plate 15 and the top metallic plate 30 of the lower unit 10. Consequently, in the closed circuit position of the interrupter, as shown in Fig. 1, the electrical circuit includes terminal stud 32 extending interiorly through terminal bushing 5, conducting clamp 33, through a suitable strap connection to the upper pressure-generating contact 11 of the upper unit 10 of the assemblage 7. The circuit then extends through the upper intermediate contact 12, the upper interrupting contact 13, through the intermediate plate 15 to the contact tubes 28. The circuit then extends through the conducting plate 30 and through a conducting strap 34 to the lower relatively stationary pressure-generating contact 11. The electrical circuit then proceeds through the lower intermediate contact 12 and through the lower interrupting contact 13 to the relatively stationary disconnect contact 17. The circuit then extends through the movable disconnect contact 18 of the assemblage 7, and through the conducting cross-bar 8 to the right-hand arc-extinguishing assemblage 7 (Fig. 1). The electrical circuit extends through the right-hand arc-extinguishing assemblage 7 in a similar manner to its passage through the left-hand arc-extinguishing assemblage 7, just described.

The movable contact assemblage generally designated by the reference character 35, and including the plates 15, 15a operating rods 16 and interrupting contacts 13, is biased downwardly in a circuit opening direction by a plurality of accelerating compression springs 36. These compression springs 36 are preferably disposed about two of the tie-rods 38 between the lowermost metallic plate 15a which is enlarged somewhat so that these tie-rods slide therethrough and the lower metallic plate 37 of the lower unit 10.

It will be noted with particular reference to Figs. 3, 4 and 5 that the units 10 are supported fixedly in desired spaced arrangement by a plurality, in this instance four, insulating tie-rods 38 surrounded by spacing sleeves 39, the latter serving to maintain the units 10 the desired distance apart. Nuts 40 disposed at the upper and lower ends of the tie-rods 38 serve to clamp the assemblages 7 to the upper clamps 33, the latter being threadedly secured and clamped to the lower ends of the terminal studs 32, 41.

The plate structure for each arc-extinguishing unit 10 will now be described. Each arc-extinguishing unit 10 includes a plurality of suitably configured insulating plates disposed in contiguous relation, and held in position by the tie-rods 38 and spacing sleeves 39. The top three plates 42, 43 and 44 of the unit 10 have enlarged apertures 45 formed therein to provide, upon alignment, the piston chambers 46. The insulating plates 42 and 43 also have centrally provided apertures 47 to accommodate slight vertical motion of the flange portion 48 of the relatively stationary pressure-generating contact 11, the latter

having a contact compression spring 49 associated therewith. The insulating plate 44 has a slightly smaller central aperture 50 to terminate downward opening motion of the relatively stationary pressure generating contact 11.

The next lowermost plate within the unit 10 is designated by the reference character 51 and also has the pair of apertures 45 provided therein. In addition, the plate 51 has an elongated slot 52 formed therein which provides a pair of outwardly extending vent passages 53 from the pressure-generating arc 54, the latter being established between the relatively stationary pressure-generating contact 11 and the intermediate contact 12. The two vent passages 53 terminate at their outer ends into a pair of vertical flow passages 55, the latter being shown more clearly in Fig. 3 of the drawings and extending downwardly within the unit 10.

The next lowermost plate 56 of the unit 10 has the apertures 45 provided therein, a pair of apertures 57, which assist in defining the vertical flow passages 55, and a centrally disposed orifice 58, through which the pressure-generating arc 54 is drawn during the opening operation.

The next plate 59 of the unit 10 has an elongated slot 60 formed therein, more clearly shown by the dotted lines in Fig. 4, and providing a pair of inlet passages 61 leading from the piston chambers 46 to the pressure-generating arc 54.

Then follows a second plate 56, a second plate 51, and a third plate 56. The next six plates in the unit 10 are designated by the reference character 62. Each of these plates 62 has a pair of enlarged apertures 45 provided therein to define, upon alignment with the other plates, the two piston chambers 46. In addition, the plates 62 have apertures 57 formed therein to assist in defining the vertical flow passages 55 (Fig. 3). Furthermore, the plates 62 have a centrally provided aperture 63 formed therein to accommodate vertical reciprocal movement of the intermediate contact 12, the latter being biased downwardly in a circuit opening direction by a compression spring 64. The compression spring 64 seats at its lower end upon a flange portion 65 integrally formed with the intermediate contact 12.

The next five plates of the unit 10 are designated by the reference character 66 and are the same as the preceding plates 62 just described, with the exception that the pair of apertures 45 for defining the piston chambers 46 are omitted. Then follows a plate 56a which is the same as the plate 56 previously described, with the exception that the apertures 45 are omitted.

Then follows a vent plate, generally designated by the reference character 67, and comprising two half plates 68, 69 spaced laterally apart to provide a pair of vent passages 70 leading laterally out of the unit 10 from the interrupting passage or chamber 71, within which the interrupting arc 72 is drawn.

Then follows a second plate 56a which, in turn, is followed by an insulating plate designated by the reference character 73, and herein termed an inlet plate. The inlet plate 73 has an elongated slot 74 provided therein, which forms two inlet passages 75 which lead from the vertical flow passages 55 to the interrupting arc 72 drawn within the interrupting passage 71 between the intermediate and movable contacts 12, 13.

Then follows a third plate 56a, a second vent plate 67, a fourth orifice plate 56a and a second inlet plate 73. The metallic plate 37 constitutes the lowermost plate of the unit 10.

The upper unit 10 of the assemblage 1 is identical to the lower unit 10, and hence need not be described.

The operation of this embodiment of my invention will now be described. To open the interrupter, suitable mechanism, not shown, but which is responsive to manual operation or to the existence of overload conditions existing in the controlled circuit, causes downward opening motion of the insulating lift-rod 9. The downward opening motion of the lift-rod 9 is accompanied by downward opening motion of the cross-bar 8 and both movable disconnect contacts 18.

The downward opening motion of the movable disconnect contacts 18 permits corresponding downward opening motion of the movable contact assemblies 35, the latter being biased downwardly by the accelerating compression springs 36. The downward opening motion of the interrupting contacts 13, as carried by the plates 15, 15a of one movable contact assembly 35, permits the compression spring 64 associated with the intermediate contact 12 to force the latter downwardly, thereby drawing a pressure-generating arc 54 between the contacts 11, 12, as more clearly shown in Fig. 2. This, of course, occurs after the stationary pressure-generating contact 11 has taken up the contact compression motion as permitted by the compression spring 49.

Further downward opening motion of the disconnect contact 18 and the movable contact assembly 35 draws a serially related interrupting arc 72 between the contacts 12, 13 after the intermediate contact 12 has been halted by the upper plate 56a. The position of the several parts at this stage of the opening operation during the interruption of relatively low currents is shown by Figs. 2 and 3.

During the interruption of such relatively low currents, the pistons 20, biased downwardly by the springs 23, move with the intermediate plate 15 to provide liquid or oil flow out of the two piston chambers 46 and through the two inlet passages 61 toward the pressure-generating arc 54. This oil flow, after striking the pressure-generating arc 54, passes away therefrom through the two pairs of vent passages 53. The oil then passes downwardly through the two vertical flow passages 55 and into the interrupting passage 71 through the two pairs of inlet passages 75. After striking the interrupting arc 72, the oil passes through the orifices 58 associated with the several orifice plates 56a and passes out of the unit 10 through the two pairs of vent passages 70. The foregoing action takes place during the interruption of relatively low currents, such as charging currents, when the pressure generated at the pressure-generating arc 54 is relatively low. The oil flow caused by the motion of the pistons 20 extinguishes one of the two arcs 54, 72 and hence clears the controlled circuit. Furthermore, downward opening motion of the movable disconnect contacts 18 causes them to separate from the relatively stationary disconnect contacts 17 to insert two isolating gaps into the circuit, as shown by the dotted lines 76 of Fig. 1.

During the interruption of relatively high currents, the pressure generated at the pressure-generating arc 54 will correspondingly be high, and will prevent downward pumping motion of the pistons 20 because of the high-pressure existing within the piston chambers 46. In this event, the high pressure generated at the pressure-generating arc 54 due to the interruption of such high current, will cause increased oil flow through the

passages in the manner previously described to cause increased oil driving force to be directed at the interrupting arc 72. Following extinction of the interrupting arc 72, and a subsidence of the pressure within the unit 10, the pistons 20 will then be able to move downwardly to cause a flushing flow of oil to pass through the unit 10 to wash out contaminated and carbonized oil.

During the closing operation, the lift-rod 9 moves upwardly carrying with it the cross-bar 8 and the two movable disconnect contacts 18. Each contact 18 strikes the relatively stationary disconnect contact 17 and carries the movable contact assembly 35 upwardly so that the contact structure is closed. Also the upward movement of the movable contact assembly 35 carries the pistons 20 upwardly within the piston chambers 46, opening the valves 26 to permit oil to flow from the region 77 through the interior of the pistons 20 and past the valves 26 into the piston chambers 46. In the closed position, the contact compression spring 49 provides the requisite contact pressure between the several contacts.

The foregoing description of one embodiment of my invention shows how I have utilized a plurality of multi-orifice interrupting units 10. The units utilize a multi-orifice type of interrupting passage 71 for high current interruption, and for low current interruption also utilize a multi-orifice pressure-generating arc passage 78. Thus, during low current interruption, the multi-orifice pressure-generating arc passage 78 functions as an interrupter in itself with the oil pumping pistons 20 producing the requisite oil driving pressure. As mentioned, during high current interruption, the pistons 20 are stalled by the high pressure until the circuit is cleared, at which time they then function as an oil flushing means.

Any number of these interrupting units 10 are capable of being stacked one on top of the other and operated in series without complicated coupling mechanism. The number of interrupting units 10 thus required will depend upon the voltage application. They may all be stacked in one column and utilized in an oil-poor breaker construction, as in United States Patent 2,479,381, issued August 16, 1949, to Leon R. Ludwig and Benjamin P. Baker, or the units may be divided into two groups for dead tank construction as shown in Fig. 1 of the drawings.

It has been found that one orifice fed by oil from an adequate pressure-generating arc is capable of interrupting 25 to 33 kv. each on high values of current, i. e., 500 to 25,000 amperes. It has also been discovered that one orifice fed by a pressure source capable of producing 40 pounds per square inch can interrupt low (leading power factor) capacity currents without restriking if the voltage does not exceed 12 to 16 kv. Thus, if a dead tank 345 kv. breaker were to be built out of interrupting units 10, such as shown in Figs. 1-5, the maximum voltage for high current operation would be 87% of 345 or 300 kv. Therefore, twelve orifices would be required, each working at 25 kv. On charging current, the restored voltage would be $345/\sqrt{3}$, or 200 kv. At 11.1 kv. per orifice, eighteen active orifices would be required. It is, therefore, evident that four interrupting units 10 would be required, such as the four shown in Fig. 1. If it is too difficult to meet the time requirements to move the contacts, say 2 1/4 inches, for the interrupting gap, plus 1 1/8 inches, say, for the pressure-generating gap, plus 1/2 inch overtravel, to create contact

pressure, then an interrupting unit 81, such as shown in Fig. 6, may be utilized. This modified type of interrupting unit 81 has two interrupting orifices and one orifice around the pressure-generating arc. In this case, a total of six interrupting units 81 would be required, that is, three on each bushing 5, 6.

The modified type of interrupting unit 81, as shown in Fig. 6, is identical to the preceding units 10, except it has one orifice, instead of two, at the pressure-generating gap, and two orifices, instead of three, at the interrupting gap. Since the gap distances for the unit 81 are less than the gap distances of the unit 10, it will take a shorter time for the contacts to move to their fully open position, as shown in Fig. 6, than it would for the contacts of the units 10.

It will be observed that Fig. 6 shows a broken vertical sectional view through the modified unit 81 on the line VI-VI of Fig. 4 so as to disclose only one piston 20, whereas, actually, there are in reality two such pistons disposed 180° apart. The view of Fig. 6, taken on such a broken sectional line, indicates more clearly the general direction of the oil flow through the unit.

As mentioned, during high current interruptions the oil pumps 20 do not follow the operating rods due to the high pressure generated by the pressure-generating arc 54, which has to be relieved by forcing the oil in the flow reservoirs 55 through the interrupting orifices 58 and out through the vents 70. After the arc is extinguished and the pressure has subsided, the spring-driven pumps 20 flush the carbonized oil from the units 10, 81. When the units open on low charging currents, the oil pumps 20 function to force oil through the orifices 58 in both the pressure-generating gap and the main interrupting gap. When the breaker is operated at no-load, the valves 26 at the lower ends of the pistons 20 produce circulation of clean oil through the interrupters.

The foregoing description of two embodiments of my invention show how I have provided a simplified type of high-voltage circuit interrupter of repeatable unit construction, so that the units may be stacked and used in any type or rating of high-voltage oil circuit breakers. It will also be noticed that the interrupting units can be stacked for series operation, and the operating forces for the contacts and for the pistons 20 are all symmetrical and balanced. It will furthermore be noticed that the piston chambers 46 are very close to the pressure-generating arc 54, and hence there results very little pressure drop through the interconnecting passage. Also the pressure arc space 73 is connected to the main interrupting passage 71 through a pair of oil reservoirs 55 of considerable volume and cross-section.

Although I have shown and described specific structures, it is to be clearly understood that the same were merely for the purpose of illustration, and that changes and modifications may readily be made therein by those skilled in the art without departing from the spirit and scope of the appended claims.

I claim as my invention:

1. A circuit interrupter of the liquid break type including at least a pair of arc-extinguishing units disposed in end-to-end relation, each unit establishing a pressure-generating arc and having a movable interrupting contact for establishing a serially related interrupting arc, an operating rod movable longitudinally of the units, means disposed between the units secured to and mov-

able with the operating rod for carrying the movable interrupting contact of one of the units, one or more pistons carried by said means operable within the other of said units, means biasing the one or more pistons to move in the direction of opening motion of the operating rod, and a sliding connection between the one or more pistons and said first-mentioned means so that during opening the one or more pistons may be stalled by the arc pressure without interference with opening motion of the operating rod.

2. A circuit interrupter of the liquid break type including an arc-extinguishing assemblage, the assemblage including at least a pair of arc-extinguishing units disposed in end-to-end relation, a pair of plates disposed on opposite ends of one of the units, an operating rod extending longitudinally of the assemblage and secured to the plates, one of the plates having a relatively stationary disconnect contact, a movable disconnect contact engaging the relatively stationary disconnect contact during the closing stroke to move the operating rod and the pair of plates, each plate carrying a movable interrupting contact, each unit having a relatively stationary pressure-generating contact and an intermediate contact, the relatively stationary contact and the intermediate contact cooperating to establish a pressure-generating arc, the intermediate contact cooperating with the movable interrupting contact to establish a serially related interrupting arc, a piston carried during the closing operation by the other of said plates and movable within said one of the units to facilitate low current interruption.

3. A circuit interrupter of the liquid break type including an arc-extinguishing assemblage, the assemblage including at least a pair of arc-extinguishing units disposed in end-to-end relation, a pair of plates disposed on opposite ends of one of the units, an operating rod extending longitudinally of the assemblage and secured to the plates, one of the plates having a relatively stationary disconnect contact, a movable disconnect contact engaging the relatively stationary disconnect contact during the closing stroke to move the operating rod and the pair of plates, each plate carrying a movable interrupting contact, each unit having a relatively stationary pressure-generating contact and an intermediate contact, the relatively stationary contact and the intermediate contact cooperating to establish a pressure-generating arc, the intermediate contact operating with the movable interrupting contact to establish a serially related interrupting arc, a piston carried during the closing operation by the other of said plates and movable within said one of the units to facilitate low current interruption, said piston having a sliding connection with said other of the plates during opening, and means biasing the piston to move in the opening direction.

4. A circuit interrupter of the liquid break type including at least a pair of arc-extinguishing units disposed in end-to-end relation, each unit having contact means therein including a movable contact for establishing an arc, an operating rod movable longitudinally of the units, means disposed between the units secured to and movable with the operating rod for carrying the movable interrupting contact of one of the units, one or more pistons carried by said means operable within the other of said units, means biasing the one or more pistons to move in the direction of opening motion of the operating rod, and a sliding connection between the one or more pis-

tons and said second-mentioned means so that during opening the one or more pistons may be stalled by the arc pressure without interference with opening motion of the operating rod.

5. A circuit interrupter of the liquid break type including an arc-extinguishing assemblage, the assemblage including at least a pair of arc-extinguishing units disposed in end-to-end relation, a pair of plates disposed on opposite ends of one of the units, an operating rod extending 10 longitudinally of the assemblage and secured to the plates, one of the plates having a relatively stationary disconnect contact, a movable disconnect contact engaging the relatively stationary disconnect contact during the closing stroke to move the operating rod and the pair of plates, each plate carrying a movable interrupting contact, each unit having contact means including said movable contact for establishing an arc within the unit, and a piston carried during the 15 closing operation by the other of said plates and movable within said one of the units to facilitate low current interruption.

6. A circuit interrupter of the liquid break type including an arc-extinguishing assemblage, the 25 assemblage including at least a pair of arc-extinguishing units disposed in end-to-end relation, a pair of plates disposed on opposite ends of one of the units, an operating rod extending longitudinally of the assemblage and secured to the 30 plates, one of the plates having a relatively stationary disconnect contact, a movable disconnect contact engaging the relatively stationary disconnect contact during the closing stroke to move the operating rod and the pair of plates, each plate carrying a movable interrupting contact, each unit having contact means including said movable contact for establishing an arc within the unit, a piston carried during the closing operation by the other of said plates and movable within said one of the units to facilitate low current interruption, said piston having a sliding 35

connection with said other of the plates during opening, and means biasing the piston to move in the opening direction.

7. A circuit interrupter of the liquid break type including an arc-extinguishing assemblage, the assemblage including at least a pair of arc-extinguishing units disposed in end-to-end relation, a pair of plates disposed on opposite ends of one of the units, an operating rod extending longitudinally of the assemblage and secured to the plates, one of the plates having a relatively stationary disconnect contact, a movable disconnect contact engaging the relatively stationary disconnect contact during the closing stroke to move the operating rod and the pair of plates, each plate carrying an axially movable interrupting contact, each unit having a relatively stationary pressure-generating contact and an axially movable intermediate contact, the relatively stationary contact and the intermediate contact cooperating to establish a pressure-generating arc, the intermediate contact cooperating with the movable interrupting contact to establish a serially related interrupting arc, a piston carried during the closing operation by the other of said plates and movable within said one of the units to facilitate low current interruption.
